BOTTLE

George W. Worthington, Castro Valley, Calif., assignor to Owens-Illinois Glass Company, Toledo, Ohio, a corporation of Ohio

Filed Sept. 28, 1960, Ser. No. 62,299

Term of patent 14 years

(Cl. D58—6)

Fig. 1 is a side elevational view of a bottle showing my new design.

Fig. 2 is an end elevational view thereof.

Fig. 3 is a bottom plan view thereof.

Fig. 4 is an enlarged fragmentary cross-sectional view taken along the line 4—4 of Fig. 1.

The side and end not shown are the same as the respective side and end shown.

The characteristic features of my design for the bottle disclosed reside in the ribbed areas above the plain side walls thereof having the configurations as shown.

I claim:

The ornamental design for a bottle, substantially as shown and described.
